UNITED STATES PATENT OFFICE.

WILLIAM W. MORGAN, JR., OF PHILADELPHIA, PENNSYLVANIA, ASSIGNOR TO E. F. HOUGHTON & COMPANY, OF PHILADELPHIA, PENNSYLVANIA, A CORPORATION OF PENNSYLVANIA.

STEAM-TRAP.

1,191,022.

Specification of Letters Patent. Patented July 11, 1916.

Application filed January 26, 1914. Serial No. 814,435.

To all whom it may concern:

Be it known that I, WILLIAM W. MORGAN, Jr., a citizen of the United States, residing in Philadelphia, Pennsylvania, have invented certain Improvements in Steam-Traps, of which the following is a specification.

One object of my invention is to improve the construction of a steam trap of the type which is controlled by a tube having a sensitive liquid therein.

A further object of the invention is to arrange the valve so that it can be readily removed and adjusted.

15 A further object is to provide means for firmly securing the rear end of the tube to the casing and yet allowing for ready removal for adjustment and repairs.

These objects I attain in the following 20 manner, reference being had to the accompanying drawings, in which:—

Figure 1, is a perspective view of my improved steam trap; Fig. 2, is a longitudinal sectional view on the line *a—a*, Fig. 3; Fig. 25 3, is a transverse sectional view on the line *b—b*, Fig. 2; Fig. 4, is a perspective view of the valve and its carrier; Fig. 5, is a perspective view showing the socket for the rear end of the tube; and Fig. 6, is a view of a 30 modification of the means for attaching the rear end of the tube to the casing.

The casing is in the general form of a sphere and made in two parts, the lower part 1 carries the mechanism and the upper part 35 2 forms the inclosing cap. In the present instance, the lower part 1 has an internal screw thread and the cap 2 has an external screw thread, so that, when the two parts are coupled together by screwing one into 40 the other, a steam tight joint, which will not suck air under vacuum, is produced and gaskets are dispensed with.

3 is an outlet in the bottom section 1 and 45 4 is an inlet, and in this inlet opening is a nozzle 5 which is secured firmly therein and projects into the steam chamber, as shown, to act as a support for the valve carrier 6, so that the carrier is free to move under the 50 action of the U-shaped tube 7 which is held low and which contains the liquid which is influenced by the changes in temperature. The carrier snugly fits the projecting portion of the nozzle which is in the form of a sharp valve seat. Mounted in the carrier 55 is a screw threaded valve stem 8 having a

valve 9 with a rounded end, as shown, which fits against the valve seat at the end of the nozzle. There is a nut on the valve stem to lock the valve in the position to which it is adjusted.

60 The carrier is grooved for the reception of the forked end 10 of the U-shaped tube, so as to cause the carrier to move with the tube, as above described. The rear end of the tube has a hooked end 11, in the present 65 instance, which engages a ledge 12 on the casing, and projecting from the casing at each side of the tube are ears 13 having extensions 14 to retain the hooked end of the tube in position when the tube engages the 70 valve carrier. The hooked end of the tube is so formed that when the opposite end is raised the hook will disengage the ledge and can be readily removed. In some instances 75 a screw 15 may be used which extends through a cross bar 16 of the casing and through an opening in the end of the tube, as illustrated in Fig. 6. The screw may have a slotted head or a head adapted to receive a wrench as desired.

80 It will be seen on referring to Figs. 2 and 6 that the rear end of the curved tube 7 is engaged by a device which does not extend through the casing so that the leakage is avoided at this point.

85 By making the trap as above described, I am enabled to readily dismantle it and to adjust the valve after it has been detached from the casing and, furthermore, by making the casing in the general form of a 90 sphere and of large area, I provide for the ready cooling of the tube when the steam is cut off, making it more sensitive than where the space is limited.

95 A steam trap of the type above described is used for any character of heating unit for regulating the flow of steam therefrom and, in many instances, these traps are located in places where they are not easy of access, consequently by making the valve 100 carrier detachable it can be removed and the valve adjusted to a nicety, and the carrier re-applied without trouble, insuring more accuracy in the adjustment than if the valve was not detachable from the 105 casing.

I claim:

1. The combination in a steam trap, of a casing having an inlet and an outlet, the inlet being at one side of the casing; a fixed 110

tubular nozzle secured to the body of the casing and in line with the inlet opening and projecting into the chamber and closed by the casing, the inner end of the tubular nozzle forming a valve seat; a valve carrier surrounding the tubular nozzle and arranged to slide thereon and extending beyond the valve seat; a valve mounted within the carrier in line with the tubular nozzle and arranged to close against the seat at the end of said nozzle; and a curved tube detachably secured to the casing at one end and arranged to detachably engage the valve carrier at the opposite end, the movement of the carrier and its valve being controlled by the tube.

2. The combination in a steam trap, of a two-part casing, one part having an inlet at

one side and an outlet at the bottom; a tubular nozzle at the inlet projecting into the chamber inclosed by the casing; a valve carrier mounted on the nozzle; a valve on the valve carrier; a recessed integral projection on the interior of the casing opposite the inlet opening; a U-shaped tube controlling the movement of the valve and having a projection at one end arranged to enter and rest in the integral projection and forked at the opposite end to engage the valve carrier.

In testimony whereof, I have signed my name to this specification, in the presence of two subscribing witnesses.

WILLIAM W. MORGAN, JR.
